US00D712408S

(12) **United States Design Patent**
Sumii et al.

(10) **Patent No.:** US D712,408 S
(45) **Date of Patent:** ** Sep. 2, 2014

(54) **CONTROLLER FOR ELECTRONIC DEVICE**

(71) Applicant: **Sony Computer Entertainment, Inc.**,
Tokyo (JP)

(72) Inventors: **Tetsu Sumii**, Tokyo (JP); **Ennin Huang**,
Tokyo (JP)

(73) Assignee: **Sony Computer Entertainment Inc.**,
Tokyo (JP)

(**) Term: **14 Years**

(21) Appl. No.: **29/453,892**

(22) Filed: **May 3, 2013**

(30) **Foreign Application Priority Data**

Feb. 19, 2013 (JP) D2012-003271

(57) **CLAIM**

The ornamental design for a controller for an electronic
device, as shown.

DESCRIPTION

FIG. 1 is a front, bottom, right perspective view of the
controller for electronic device showing our new design;
FIG. 2 is a rear, top, left perspective view thereof;
FIG. 3 is a front, top, left perspective view thereof;
FIG. 4 is a front elevational view thereof;
FIG. 5 is a rear elevational view thereof;
FIG. 6 is a left side elevational view thereof;
FIG. 7 is a right side elevational view thereof;
FIG. 8 is a top plan view thereof; and,
FIG. 9 is a bottom plan view thereof.

1 Claim, 6 Drawing Sheets
